BALL POINT PEN OR SIMILAR ARTICLE

William S. Sherman, Chicago, Ill., assignor to Cory Corporation, Chicago, Ill., a corporation of Delaware

Application June 29, 1956, Serial No. 42,095

Term of patent 14 years

(Cl. D74—17)

Figure 1 is a side elevational view of a ball point pen showing my new design;

Fig. 2 is a front elevational view thereof as it appears with the guard sleeve pushed back and the point exposed in writing position;

Fig. 3 is a top plan view thereof; and

Fig. 4 is a horizontal sectional view through the guard sleeve taken on the line 4—4 of Fig. 1 and viewed in the direction of the arrows.

I claim:

The ornamental design for a ball point pen or similar article, substantially as shown.
